UNITED STATES PATENT OFFICE.

HENRY D. JACKSON, OF MATTEAWAN, NEW YORK.

PLUME.

SPECIFICATION forming part of Letters Patent No. 361,948, dated April 26, 1887.

Application filed February 26, 1887. Serial No. 229,007. (No model.)

To all whom it may concern:

Be it known that I, HENRY D. JACKSON, a citizen of the United States, residing at Matteawan, in the county of Dutchess and State of New York, have invented certain new and useful Improvements in Plumes; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to plumes which are particularly designed for decorating horses and animals, and has for its object the construction of a plume which can be quickly lowered by folding, as when it is desired to blanket or cover the animal. The plume will yield slightly at the end of each swaying movement for relieving the connection between it and the harness of the usual strain.

The improvement consists in having a hinge-
25 joint in the shank or standard of the plume and surrounding the same by a coil-spring or equivalent means for stiffening the joint. The coil-spring is preferable in that it will permit a yielding of the joint at the end of each swaying movement of the plume and can be quickly applied and conveniently operated when it is desired to fold the plume.

The improvement consists in the novel features hereinafter more fully described, 35 claimed, and shown in the annexed drawings, in which—

Figure 1 is a side elevation of a plume embodying my improvement. The dotted lines show the yielding motion at the end of the 40 swaying movement in each direction; Fig. 2, a view similar to Fig. 1, showing the plume lowered or folded; and Fig. 3 is a front view embodying a modification.

The plume is of ordinary construction, and 45 is composed of the tuft A and the standard made in two parts, B and B', hinged together, so that a portion of one part extends on each side of the plane of the other part when the plume is folded, and presents a purchase for

the coil-spring C on each side of the pivotal connection between the two parts for holding the plume folded and from resting upon the animal. The coil-spring surrounds and extends on each side of the joint for stiffening it. One end may be fixed and the other end movable along the standard for freeing the joint and permitting the folding of the plume. The spring is compressed by grasping the movable end thereof between the fingers and moving it toward the fixed end till the joint is 50 cleared, when the plume can be folded. The spring is then released, and, exerting an equal force on the fixed part B' of the standard, on each side of the pivotal connection b, holds the plume in its lowered or folded position. 55

The standard is generally provided with a shoulder at each end, and the coil-spring will be held between said shoulders. In this case both ends of the spring are movable, and either end may be compressed, as desired. In 70 case the spring is stiff and small and does not afford a broad purchase for the fingers, the same can be had by the washer D, mounted upon the standard. The washer is provided with arms d, projecting in opposite directions 75 therefrom, which offer a sure purchase for the fingers when compressing the spring. The lower end of the standard is provided with the socket E and set-screw e for clamping the plume to any suitable projection in the usual 80 manner.

Having thus described my invention, what I claim, and desire to secure by Letters Patent, is—

1. A plume having a standard composed of 85 two parts hinged together and a stiffener surrounding the joints and permitting a slight yielding of the latter, substantially as and for the purpose described.

2. The combination, with the plume having 90 a standard composed of two parts hinged together, of the coil-spring for holding the plume upright and lowered, substantially as set forth.

3. The combination, with the plume having 95 a standard made of two parts hinged together and the compressible stiffener, of the bearing-washer located at one end of the stiffener and presenting a bearing-surface for the fingers to

obtain a purchase upon, substantially as described.

4. The combination, with the plume having a standard composed of two parts hinged together, of the compressible stiffener surrounding said joint for strengthening it and holding the plume upright and adapted to press upon one of the parts on each side of the

pivotal connection and hold the plume lowered or folded, substantially as set forth. 10

In testimony whereof I affix my signature in presence of two witnesses:

HENRY D. JACKSON.
